GOTTLOB HONOLD, OF STUTTGART, GERMANY.

APPARATUS FOR STARTING INTERNAL-COMBUSTION ENGINES.

1,043,595.

Specification of Letters Patent.

Patented Nov. 5, 1912.

Application filed May 23, 1911. Serial No. 628,984.

To all whom it may concern:

Be it known that I, GOTTLÖB HONOLD, a subject of the Emperor of Germany, residing at Stuttgart, Germany, have invented 5 certain new and useful Improvements in Apparatus for Starting Internal-Combustion Engines; and I do hereby declare the following to be a full, clear, and exact description of the invention, such as will enable others skilled in the art to which it appertains to make and use the same.

This invention relates to apparatus for starting internal combustion engines, and particularly to apparatus adapted to the 15 method of starting which consists in withdrawing the old charge from a cylinder or cylinders, then introducing fresh combustible mixture therein, and finally igniting the 20 fresh mixture. Various modifications of this method have already been devised, differing principally in the manner of introducing the fresh combustible mixture into the cylinders. However, in these cases either the old charge was sucked out of one 25 opening and the fresh mixture sucked in another opening, or the old charge was forced out of one opening by a fresh charge which entered another opening. In all cases 30 two openings in each cylinder were necessary, one for withdrawing the old charge, and the other for introducing the fresh mixture. If the inlet and outlet valves of the 35 cylinders were not used for this purpose, special openings and operating mechanism were required, all of which obviously complicated the construction of the cylinders and sometimes interfered with the normal 40 operation of the engine.

In accordance with my invention, the old 45 charge is first withdrawn through a special opening in the cylinder, and then the fresh combustible mixture is forced into the cylinder through the same opening. A valve interposed between the exhausting device and the cylinder is operated after the pressure in the cylinder is sufficiently reduced to connect the carbureter with the special opening in the cylinder, whereby atmospheric pressure forces the fresh combustible mixture from the carbureter into the cylinder. The 50 fresh combustible mixture which passes into the exhausting device at the same time, may, if desired, be wholly or in part forced into the cylinder. For multiple cylinder engines, a double acting air pump is employed and 55 all the cylinders having their inlet and out-

let valves closed are connected to the suction side of the pump, while those cylinders having their inlet or outlet valves open, are connected to the pressure side of the 60 pump. In this way, those cylinders which have closed valves will receive fresh mixtures, while the part of the fresh combustible mixture which, at the same time, passes into the suction side of the pump may be 65 allowed to pass to the pressure side of the pump by means of an automatic valve, so that at the next stroke of the pump the fresh combustible mixture therein will be 70 forced into those cylinders which have their inlet or exhaust valves open and force out the gases therein. In this way it is possible to provide all the cylinders of a multiple cylinder engine with fresh combustible mixture whether their valves are open or 75 closed.

Inasmuch as this invention requires that the combustion space in the cylinder be exhausted before the fresh, combustible mixture is introduced, the engine crank must 80 be brought to such a position that the inlet and exhaust valves of the cylinder of a single cylinder engine, or of some of the cylinders of a multiple cylinder engine, are closed. This position may be indicated by 85 an indicating device, such as a movable flap interposed in the conduit between the exhausting device and the cylinder, so that the flap will show the direction of flow of the gases. For multiple cylinder engines this 90 flap may be used also for the purpose of indicating which cylinders have open valves and which have closed valves, so that it will be apparent which cylinders are to be exhausted and then filled with fresh mixtures. 95 This feature may be of importance, since ordinarily only those cylinders with closed valves have their pistons in the compression or working part of the stroke. If the old charge is withdrawn from a cylinder with 100 open valves, the flap moves only to one side because the air enters the cylinder through the open valve and prevents a diminution of pressure within the cylinder, but if the valves of that cylinder are closed, then the 105 combustion space is first exhausted and then filled with fresh mixture, thereby causing the flap to move toward one side, and then toward the other during each stroke of the pump. However, the indicating device may 110 be so constructed that it moves only in the direction produced by the inflow of gases to

the cylinder by means of an abutment or the like. The indicating device may also serve to enable the operator to properly regulate the speed of the pump for either single or 5 multiple cylinder engines since it indicates after each stroke of the pump whether the pressure is equalized in the pump and the cylinder after the fresh mixture is drawn in, and whether a subsequent stroke should take 10 place.

In the accompanying drawings showing diagrammatically several modifications of the idea embodied in this invention, Figure 1 illustrates the arrangement for a single 15 cylinder engine; Fig. 1^a shows the position of cock *e* when fresh combustible mixture passes from the carbureter to the cylinder; Fig. 2 shows the arrangement wherein a jet injector is employed for the exhausting de- 20 vice; Fig. 2^a shows the position of cock *e* when fresh combustible mixture passes from the carbureter to the cylinder; Fig. 3 shows the arrangement applied to a multiple cylinder engine; Fig. 4 shows a spark plug par- 25 ticularly well adapted for this invention; and Fig. 5 shows a modified arrangement.

Referring particularly to Fig. 1, *a* designates a cylinder of an internal combustion engine provided with a spark plug *b* and a 30 special opening *c* for the passage of the gases out of and into the combustion space of the cylinder in starting the engine. The carbureter *d* may be connected with the exhaust conduit *f* by means of a cock *e*, as 35 shown in Figs. 1 and 2, or by means of the valve *e*₁ shown in Fig. 3. The exhausting device for withdrawing the old charge is the pump *g* in Figs. 1 and 3 or the jet injector *g*₁ in Fig. 2. The cock *m* or other 40 suitable device prevents the force of the explosion in the engine cylinder from acting on the exhausting device or the carbureter. To start the engine with the apparatus 45 shown in Fig. 1, the engine crank is first brought to the most favorable location. The pump *g* is then operated so as to exhaust the old charge from the combustion space of the cylinder *a* through the opening *c* and the conduit *f*, during which period 50 the inlet and outlet ports of the engine and the cock *e* are closed, as shown in Fig. 1, while the valve *m* is open. As soon as the pressure in the cylinder is sufficiently reduced, cock *e* is turned to the position shown 55 in Fig. 1^a and mixed air and fuel gas flow from the carbureter *d* into the conduit *f* and thence into the cylinder and into the suction side of the air pump. After the pressure in the cylinder and the air pump 60 is equalized, the cock *e* is closed and the operation is repeated if necessary. The old charge withdrawn from the cylinder is preferably automatically expelled from the pump through the check valve *l* so that the 65 fresh combustible mixture which subse-

quently flows into the pump does not mix with the old charge. In this way the combustion space in the cylinder is filled with a fresh combustible mixture, and when the cylinder is sufficiently charged with fresh 70 mixture the conduit *f* is cut off from the cylinder by means of the cock *m* and the combustible material then ignited by means of the ignition plug *b* which is supplied with ignition current from any suitable 75 source indicated by *b*₁.

In the arrangement shown in Fig. 2, the pump is replaced by a jet injector *g*₁ which may be operated by compressed air or compressed gas from the tank *n* or other suitable source. The three-way cock *e* is so arranged that when the old charge is being exhausted from the cylinder, the carbureter is disconnected from the conduit, but when the cock is turned to introduce the fresh 85 combustible mixture into the cylinder *a*, the injector is disconnected from the carbureter and the cylinder. After the injector has sufficiently reduced the pressure in the cylinder, the cock *e* is turned to the position 90 shown in Fig. 3, whereupon the combustion space is filled with fresh combustible mixture. In this arrangement the operation of exhausting and filling the cylinder may also be repeated, if desired, so as to produce a 95 more efficient explosion for starting. The cock *m* is then closed and the fresh combustible mixture ignited as before.

Fig. 3 shows a four-cylinder combustion engine having the combustion spaces connected by pipes to a distributing valve *i* and thence through one conduit *k* to one side of a double acting pump *g* and through another conduit *f* to the other side of the pump. The valve *i* is so arranged that the 100 two alternate cylinders may be connected to either side of the pump, while the other two would be connected to the other side of the pump. The conduit *f* contains the indicating device *h* comprising a flap as 110 shown which moves to one side of the vertical or the other, depending upon the direction of flow of the gases through the conduit *f*. Or, if desired, the flap may be prevented from moving to one side of the 115 vertical by an abutment or the like so that only the flow of gases into the cylinders from the carbureter would be indicated. The cock *e* of Figs. 1 and 2 is replaced in Fig. 3 by a valve *e*₁ which is held closed 120 in the position of rest by a spring, but is automatically opened at the end of the stroke of the pump by the operation of the check valve and the pivoted lever co-acting therewith, as shown. In Fig. 3, the conduit *k* is in communication with cylinders 2 and 4 whose valves are open, while conduit *f* is in communication with cylinders 1 and 3 whose valves are closed.

In the arrangement shown in Fig. 3, the 125

first stroke of pump *g* causes a diminution of pressure in cylinders 1 and 3, and at the end of the stroke the valve *e*₁ automatically opens so that fresh combustible mixture from the carbureter enters these cylinders and the suction side of the pump. As soon as the pressure has been equalized, the valve *e*₁ is closed with the downward stroke of the pump while the fresh combustible mixture in the pump passes through the check valve *l* into the upper part of the pump cylinder. During the next upward stroke of the pump, the same operation is repeated upon the exhaust side, while the fresh combustible mixture which has passed to the pressure side of the pump flows through conduit *k* and distributing valve *i* to the combustion space of cylinders 2 and 4, whose valves are open. In this way the old charge in cylinders 1 and 3 is first sucked out by the pump and then fresh combustible mixture is introduced through conduit *f*, while the old charge in cylinders 2 and 4 is forced out of the open valves by the fresh combustible mixture entering therein through conduit *k*. It is desirable to introduce the gas into the cylinder as near to the ignition device as possible. For this reason the spark plug *b* shown in Fig. 4 is particularly well adapted to the purpose, since the fresh combustible mixture is introduced into the cylinder through the nipple *o* of the spark plug itself, as indicated in Fig. 4.

It is obvious that the arrangements may be variously modified by different combinations of the elements described for different purposes. The check valve *l* shown in the pump of Fig. 1 is replaced in Fig. 5 by a three-way cock *p*. To exhaust the cylinder the cocks *e* and *p* are placed in the position shown and the pump piston is pulled up, whereupon the old charge in the cylinder is partly drawn into the suction chamber of the pump. The cock *p* is then turned so that the suction chamber of the pump exhausts to the atmosphere. If desired the same operation may be repeated until the cylinder is sufficiently exhausted. Preferably with the pump piston in the upper position, and with cock *p* in the position shown in Fig. 5, the valve *e* is opened so that fresh combustible mixture flows into the cylinder and also into the suction chamber of the pump. Then by forcing the pump piston down, the fresh combustible mixture therein may be forced into the cylinder so that the combustible mixture in the cylinder is more highly compressed and therefore effects a more efficient explosion for starting upon subsequent ignition.

Having thus described my invention, what I claim is:

1. Apparatus for starting an internal combustion engine, comprising a conduit con-

nected to the combustion space of the cylinder or cylinders of the engine, an exhausting device connected to the conduit to withdraw the old charge from the cylinder or cylinders and thereby reduce the pressure therein, a carbureter connected to the conduit to supply fresh combustible mixture to the cylinder or cylinders after the pressure is reduced therein, and an ignition device in said combustion space or spaces to ignite the fresh combustible mixture therein, whereby the engine is started by withdrawing the old charge from an opening to the cylinder or cylinders, introducing the fresh combustible mixture therein through the same opening and igniting the mixture.

2. Apparatus for starting internal combustion engines, comprising an ignition device in a cylinder of said engine, a conduit to said ignition device; an exhausting device connected to said conduit to withdraw the old charge from the combustion space of each cylinder and thereby reduce the pressure therein, and a carbureter connected to the conduit to supply fresh combustible mixture to the cylinder after the pressure is reduced therein, whereby the engine is started by withdrawing the old charge from an opening to the cylinder, introducing the fresh combustible mixture therein in close proximity to the point of ignition through the same opening, and igniting the mixture.

3. Apparatus for starting an internal combustion engine, comprising a conduit connected to the combustion space of the cylinder or cylinders of the engine, an exhausting device connected to the conduit to withdraw the old charge from the cylinder or cylinders and thereby reduce the pressure therein, a carbureter connected to the conduit to supply combustible mixture to the cylinder or cylinders after the pressure is reduced therein, an ignition device in each of said combustion spaces to ignite the fresh combustible mixture therein, and an indicator in said conduit for indicating the direction of flow of the gases therein.

4. Apparatus for starting multiple cylinder combustion engines, comprising pipes connected to the combustion space of each cylinder, a distributing valve adapted to connect said pipes in groups, a conduit connected to the valve so as to be placed in communication with one group of pipes or the other, another conduit connected to said valve so as to be in communication with the other of said groups of pipes, a double-acting pump having one side connected to one of said conduits and the other side connected to the other of said conduits, and a carbureter connected to one of said conduits, whereby the combustion space of those cylinders whose valves are closed may be exhausted and then filled with fresh combustible mixture from the carbureter, while those

cylinders whose valves are open are supplied with fresh combustible mixture by pressure.

5. Apparatus for starting internal combustion engines, comprising a conduit connected to the combustion space of a cylinder or cylinders of the engine, an exhausting device connected to the conduit to withdraw the old charge from the cylinder or cylinders and thereby reduce the pressure therein, a carbureter connected to the conduit to supply a fresh combustible mixture to the cylinder or cylinders after the pressure is reduced

therein, an automatic valve operated by the pump to connect the carbureter with said conduit, and an ignition device in the combustion space of the cylinder or cylinders for igniting the combustible mixture therein.

In testimony whereof I affix my signature, in presence of two witnesses.

GOTTLOB HONOLD.
